UNITED STATES PATENT OFFICE.

JAMES J. SULLIVAN, OF LONG ISLAND CITY, NEW YORK.

WRAPPING-MACHINE.

No. 851,907.

Specification of Letters Patent.

Patented April 30, 1907.

Application filed October 5, 1905. Serial No. 281,457.

To all whom it may concern:

Be it known that I, JAMES J. SULLIVAN, a citizen of the United States of America, and a resident of Long Island City, county of 5 Queens, State of New York, have invented certain new and useful Improvements in Wrapping-Machines, of which the following is a specification, reference being had to the accompanying drawings, forming a part thereof.

My invention relates to machines for automatically wrapping articles with a suitable material, such as lead- or tin-foil, and for applying and securing a label thereto.

15 The main object of my invention is to provide a small, simple, compact and light running machine for this purpose, whereby the same will be inexpensive to build, will occupy but small space, and will be capable of 20 a high speed of operation.

In carrying out my invention I provide means for operating simultaneously on several articles in successive stages in the machine, whereby a considerable saving of time 25 is effected; and I arrange the several mechanisms in groups, whereby the various parts of the machine may be readily reached for purposes of cleaning or repair without it being necessary to dismantle the machine 30 piecemeal.

It is a further object to reduce to a minimum the distance of travel of the various working parts, so as to avoid undue friction and wear, and reduce shock due to momentum and inertia.

35 I also aim to fold the wrapper in such a way as to effectually seal the article contained therein, the ends of the wrapper being folded over, and then tucked under, to be 40 finally permanently secured in position by the label.

To these various ends, my invention consists in many novel details of construction and combination of parts, some of them radically new in themselves, and others in their combination and modes of operation, all as 45 will be clearly set forth hereinafter.

In order that my invention may be fully understood, I will describe in detail a machine embodying my invention, having reference to the accompanying drawings illustrating same, and will then point out the novel features in claims.

Figure 1 is a view in side elevation of a 55 machine embodying my invention. Fig. 2 is a view in central vertical longitudinal sec-

tion therethrough. Fig. 3 is a top view with the overhead parts removed. Fig. 4 is a view in vertical section upon the plane of the line 4—4 of Fig. 3, showing the machine substantially in rear elevation, but with certain of the overhead parts removed. Fig. 5 is a view in vertical transverse section upon the plane of the line 5—5 of Fig. 2. Fig. 6 is a view in vertical transverse section upon the line 6—6 of Fig. 2. Fig. 7 is a detail view showing an under side view of the main reciprocating plate and certain correlated parts. Fig. 8 is a detail view showing certain connections for the delivery mechanism. Fig. 9 is a detail view of the knife or cutter for the wrapper, and certain parts of the knife operating mechanism. Fig. 10 is a detail view of a finger or steadyng device employed in connection therewith. Fig. 11 is a detail 75 sectional view of certain parts upon the line 11—11 of Fig. 2. Fig. 12 is a detail view in perspective of a folding plate employed. Figs. 13, 14, 15, 16, 17, 18, 19, 20, 21, 22 and 23 are diagrammatic views showing the operation of wrapping an article. Fig. 24 is a view in perspective of an article with the first wrapper completely finished, but before the label is put on.

The particular machine illustrated in the 85 accompanying drawings is designed for the purpose of wrapping pieces of chocolate with lead foil, and afterward affixing a second wrapper, which constitutes a label, and which I will here refer to as a label.

90 It will be of course understood that the machine is adapted for wrapping other articles, and that such articles may be wrapped with other material, and that the particular description herein is intended for the purpose 95 of describing the present machine, and is in no way intended to be a limitation on the specific construction, form or adaptability of the apparatus.

In the machine herein, a frame 1 serves as 100 a support for the various parts, including the main drive shaft 2 which is journaled in stationary bearings upon the machine, and is arranged transversely of the machine at about the middle thereof. This shaft is 105 driven from a suitable source, not shown, through gearing 3, and carries the main cams and other devices which operate the moving parts of the machine. One of these devices comprises a mutilated gear-wheel 4, having 110 teeth throughout approximately one half of its circumference, and a plain portion

throughout the other half of its circumference. This mutilated gear-wheel is arranged to engage with mutilated pinions 5 and 6 arranged, respectively, upon stub shafts 7 and 8, each of said pinions arranged to be given one complete rotation during one half of the rotation of the gear 4, and to remain at rest during the other half of the rotation of the said gear-wheel.

10 Mounted upon the stub shaft 7, and secured fast to the pinion 5, is a crank arm 9, which carries a crank pin 10 connected by means of a pitman 11 with a depending bracket 12 from the main reciprocating plate 13. Mounted upon the stub shaft 8 is a crank arm 14, which is secured fast to the pinion 6, and which carries a crank pin 15 to which is connected a pitman 16. The pitman at its other end (see more particularly Figs. 2, 4 and 5) is connected to an arm 17, in turn secured by a pin 18 to a cross head 19. The cross head 19 is secured fast upon a vertical plunger rod 20, which carries at its upper end the overhead portions of the machine. Intermediate its ends the said plunger 20 is mounted in, and guided by, a vertical standard 21 secured to, or formed as a part of, the main frame of the machine. The cross head extends laterally toward the opposite side of the machine, and carries two anti-friction guide rollers 22, which engage with a vertical guide-way 23. The guide-way 23 and rollers 22 form vertical bearings for the cross head 19 to maintain the parts in proper relative positions as they are reciprocated by rotation of the crank arm 14. The main reciprocating member or plate 13 is arranged to slide in suitable ways 24 (see particularly Fig. 6), formed as a part of, or secured to, the frame 1, the reciprocation thereof being effected by rotation of the mutilated pinion 5 and crank arm 7 as aforesaid. A stationary top plate 25 is arranged immediately above the upper face of the plate 13, said stationary plate 25 being secured to, or formed as a part of, the said frame. This plate is provided longitudinally with a central slot 26, in which is fitted a bar 27, constituting a carrying member, as will hereininafter appear. This carrying member is secured by means of screws 28 to the reciprocating plate 13, the upper face of the said bar being about level with the upper face of the stationary top plate 25. The reciprocating plate 13 also carries with it an overhanging pusher plate 29, secured by screws 30 to laterally extending portions 31 of the said reciprocating plate 13, the said pusher plate overhanging the stationary top plate 25 and 60 the bar 27, as will be clearly seen by reference to Figs. 3 and 6. The reciprocating plate 13 further carries a bar 32 secured beneath its lower face by means of screws 33, the outer end of said bar provided with an upwardly projecting portion 34 constituting

the stationary member or jaw of a gripper, that is to say, a gripper member stationary upon the reciprocating plate. A movable bar 35 is mounted between the lower face of the plate 13 and the said stationary gripper bar 32, said movable gripper bar having a limited longitudinal movement with relation to said plate 13 and stationary gripper bar 32, said bar 35 being slotted at the portion surrounding the screws 30 to permit of said limited movement. At its forward end the said movable gripper bar 35 supports and carries a pivoted gripping jaw 36, the same being pivoted thereon, and having a depending finger 37 which engages an opening in the stationary gripper bar 32, as will be clearly understood by reference to Fig. 2 of the drawings. At its rear end the movable gripper bar carries a small plunger 38, which enters a cylindrical opening 39 in the bracket 12 and engages a compression spring 40 contained therein. The said compression spring normally tends to force the movable bar 35 forward with respect to the stationary bar 32, to tightly close the gripping jaws 34 and 36. 70 75 80 85 90 95 100 105 110 115 120 125 130

Pivots supported against the under face of the stationary bar 32 is a cam piece 41, and, secured to the movable bar 35 by means of a stud 42, the shank of which passes through a slot in the stationary bar, is a follower roller 43. The cam piece 41 has two notches 44 and 45, each of which is adapted to engage the follower roller 43. The notch 45 is, however, at a greater distance from the pivotal center of the cam piece 41 than is the notch 44. When the follower roller 42 is resting in the notch 43 of the cam piece 41, the movable bar 35 will be in its relaxed or forward position with respect to the stationary bar 32, and in this position the gripper jaws 34 and 36 will be closed. When, however, the follower roller 43 is in engagement with the notch 45 of the cam piece 41, the bar 35 will be in its rearward position with respect to the bar 32, and the movable jaw 36 will have been swung open upon its pivot. A portion of the two bars 32 and 35 are shown in the latter position in Fig. 19, the movable jaw 36 being shown as swung open with respect to the stationary jaw 34. 125 130

In order that the cam piece 41 may be operated, it is provided with a lateral extension or arm 46, in the path of movement of which is arranged a stationary abutment 47 secured to the framework 1. As the plate 13 and parts carried thereby move forward the arm 46 is engaged by the stationary abutment 47 to throw the cam piece 41 from a position with its notch 45 in engagement with the roller 43, to a position with its notch 44 in such engagement, in which latter position the parts are shown in Fig. 7. The engagement of the arm 46 with the abutment 47 will be at substantially the termination of the forward movement of the said plate and 125 130

parts carried thereby, whereby the grippers will be snapped shut at just about the completion of such movement. The parts will be held in this position by means of the 5 spring 40 during the rearward movement of the plate and until the cam piece 41 is engaged by a finger 48, carried by a lever 49 mounted upon a shaft 50. A cam 51 upon the main shaft 2 engages a follower roller 52 10 carried by a lever 53, which is also secured to the rock shaft 50, and the said cam 51, in its rotation, will effect the rocking of the shaft 50 to vibrate the lever 49, and thus to cause the finger 48 to engage the lateral arm 46 of 15 the cam 41 at the required moment. A spring 54, secured at one end to the frame, and at the other end to the lever 49, serves as a yielding pressure device to hold the cam follower up in engagement with the face of its 20 cam.

In addition to carrying the finger piece 48, the lever 49 engages a yoke piece which projects downward from a sliding folder plate 56. This plate 56 is mounted to slide in ways 25 in the frame of the machine, and has a portion which extends upward, forward and laterally in front of the forward end of the top plate 25, as will be seen in Figs. 2 and 12. The vibration of the lever 49, as above set 30 forth, will effect a reciprocation of the folder plate 56 for the purpose of accomplishing the first fold of the wrapper, as will be presently explained, the plate 56 being shown in its rearmost position in Fig. 2, and as having 35 moved forward in Fig. 15.

The wrapping material, which, in the present instance, is lead foil, as shown at 57 in the drawings, is supplied from a reel or other source, not shown, the forward end thereof 40 passing over a direction roller 58, thence over the face of the top plate 25 and bar 27, beneath the overhanging pusher plate 29, to a point at about opposite the line x , Figs. 1, 2 and 3 of the drawings. As before stated, the 45 bar 27 constitutes a carrying member for the wrapping material, and, acting in conjunction with this carrying member, is a clamping finger 59. This clamping finger is secured to a hub 60 mounted to slide upon a rectangular rock shaft or bar 61, itself mounted to rock in bearings 62 upon the main frame of the machine.

A spring 63 coiled about one end of the shaft, tends to rock the same in one direction, causing the finger 59 to normally bear 55 with a yielding pressure toward the bar 27. The said hub 60 is provided with a handle or hand piece 64, by which the shaft may be rocked and the finger thrown upward when 60 desired, as in first threading up the machine. For the purpose of rocking this shaft during the normal operation of the machine, I have provided the same with a segment of a gear 65, which is arranged in mesh with a gear

sector 66, constituting one portion of a bell 65 crank lever, the other arm 67 of which carries a cam follower roller 68. This roller is arranged to be engaged by a crown cam 69 disposed upon the face of the mutilated gear-wheel 4. The action of the cam will rock 70 the bell crank lever 66, 67 upon its support to cause the rocking of the shaft 61 and the lifting of the finger 59. The said cam will be so timed with relation to the reciprocating movement of the plate that the finger 75 will be so lifted during the rearward movement of the plate, and will be left free to clamp the wrapping material between itself and the bar 27 during the forward movement of the plate. The clamping finger 59 and 80 the carrier bar 27 will then act as a feeding device to intermittently feed the wrapping material forward step by step upon the reciprocation of the main reciprocating plate 13.

Resting upon the top of the plate 25, near 85 the rear thereof, is a retarding or checking device comprising a finger 70 formed by bending a lever 71 at right-angles to itself, said lever pivoted at 72 to the frame of the machine. The lever 71 carries a roller 73, 90 which rests upon a cam 74 secured to, and carried by, the plate 13. During certain parts of the movement of the plate 13, the cam 74 will lift the lever 71 and the finger 70, while, during other parts of its movement, it will allow the said finger to rest upon 95 the wrapper, permitting it to act at such times as a retarding or checking device.

Arranged immediately above the top plate and the carrying bar 27, at a point just in 100 advance of the front of the pusher plate 29 when the said plate is in its rearmost position, is a magazine 75 for the articles to be wrapped. These articles may be arranged loosely in the said magazine, the lowermost 105 article resting upon the wrapping material upon the carrying plate 27. When the plate 13 is given a forward movement to feed the wrapping material forward, the lowermost article beneath the magazine is also fed forward by engagement with the front face of 110 the pusher 29, and the amount of such movement will be sufficient to bring the said article immediately beneath a plunger 76 and above a vertical supporting device 77. The 115 supporting device 77 comprises a stem 78 mounted to slide in a bearing 79, and a bifurcated or forked portion 80 guided in bearings 81, said portions bifurcated or forked in order to straddle the bars 32 and 35. A 120 spring 82 resists downward movement of the device, but permits such downward movement under yielding pressure. When in its uppermost position the top edges of the forked portion 80 are about level with the 125 upper surface of the top plate 25 and of the upper surface of the bar 27, but at a point a little in advance of the forward ends thereof,

so that the wrapper and article resting thereon may be received by the said supporting device as they are fed forward.

Located at a point just in advance of the finger 59, and between the said finger and the path of movement of the plunger 76, is a severing device for the wrapper and a yielding device for steadyng the portion of the wrapper so severed. The severing device 10 comprises a blade 83 carried by a lever 84 pivotally mounted upon a spindle 85, and a housing or shroud 86. This device is shown in detail in Fig. 9, and appears also clearly in Figs. 3 and 14. The shroud 86 is loosely 15 pivoted upon a spindle 85, and is connected with the lever 84 by means of a yielding connection 87, as clearly shown in Fig. 9. The severing device is operated by means of a cam 88 upon the main shaft 2, said cam 20 88 engaging a cam roller 89 carried by an arm 90 upon a vertically reciprocating spindle 91.

The spindle 91 is mounted to move in stationary bearings 92, and is normally pressed 25 downward to keep the roller 89 against the face of the cam 88 by means of a compression spring 93. A link 94 connects the arm 90 with the lever 84, the vertical movement of 30 reciprocation of the said arm 90 imparting thereby a rocking movement of the lever 84 upon the spindle 85. The cam 88 is so timed with relation to the feed for the wrapping material that the severing device will descend to sever a portion of the material 35 during the time the material is at rest after a step by step forward movement. The blade 83 and housing 86 are so relatively arranged that the housing 86 will rest upon the wrapping material before the blade commences 40 to cut. This will have the effect of steadyng the wrapping material and holding the same while the blade does the severing. Further, a notch 95 is preferably provided in the top plate 25 and bar 27 for receiving 45 the severing edge of the blade so as to insure the complete severance of the material, and the action of the housing or shroud will be to prevent the blade from carrying the material down into the notch, as will be well understood. In order to steady the piece of wrapping material which has been severed, I have provided a member 96 having a bifurcated or forked portion comprising two fingers 97, 50 97, arranged to straddle the supporting device 77 and to rest upon the severed portion of material at points upon opposite sides of the path of movement of the plunger 76. This steadyng member 96 is pivotally mounted upon the spindle 85 which carries the severing device, and a spring 98 tends to force 55 the said fingers downward to press upon the wrapping material with a yielding pressure. The spindle 85 is secured fast to the lever 84 of the cutter device, and therefore rocks with 60 the said lever, and this spindle is provided

with a pin 99 (see Fig. 10), which is received in a slot 100 in the hub of the member 96. The slot 100 permits a certain amount of lost motion between the spindle 85 and the member 96, but the spindle 85, in its rocking 70 movement, finally lifts the steadyng device 96 at the proper moment when it is desired to feed the fresh piece of material beneath same.

After the piece of the wrapping material 75 which extends beyond the knife blade 83 has been severed thereby, the plunger 76 is moved downward to engage the article resting thereon and upon the supporting device 77, so as to force the article down through an 80 opening 101, and, at the same time, forcing the supporting device 77 downward against the resistance of the spring 82. The head of the plunger 76 is forked or bifurcated, as will be seen more particularly by reference to 85 Fig. 5, it being provided with shouldered portions 102 adapted to engage the article to be wrapped near the ends thereof, as the plunger descends. The plunger 76 is carried by a head 103, which is in turn mounted upon, 90 and carried by, the plunger rod 20, so that reciprocation of the plunger head 76 will be effected by reciprocation of the plunger rod 20 by the means and in the manner above set forth. I prefer to provide for a slight yielding 95 between the plunger head 76 and the supporting head 103 to prevent undue shock upon the edges of the article to be wrapped, the present construction for this purpose comprising a square stem 104 mounted to slide 100 in the head 103, with small compression springs 105 arranged between the said head 103 and a shoulder upon the stem. The square stem will prevent the plunger from turning while permitting relative vertical 105 movement, and the springs will yieldingly resist such vertical movement.

In order to prevent damage to the parts in case the machine should operate without an article being beneath the plunger 76, whereby the plunger 76 will fail to depress the supporting device 77, I have provided auxiliary means which will compel the depression of the said plunger, comprising a lever 106 secured to the rock shaft 50 and arranged to engage an abutment 107 carried by the stem 78 of the supporting device 77 (see particularly Figs. 1, 2 and 6). The shaft 50, it will be remembered, is caused to rock by means of the cam 51, and the said cam is timed to 110 operate at such a period in the cycle of the machine as to depress the device 77 in case it shall not have been depressed by the normal means, in time to move same out of the path of the reciprocating plate 13 and parts 115 120 secured thereby.

The opening 101, above referred to, is arranged between the forward end of the top plate 25 and the rear end of a presser plate 108, the said presser plate 108 being a hori- 130

zontal plate provided with arms 109 arranged to bound the ends of the said opening 101 and to form means by which the said presser plate may be pivoted to the said top plate 25. Near its outer end the plate carries a vertical plunger 110, which enters a housing 111 secured to the pedestal 21, and containing a compression spring 112. The spring 112 tends to force the presser plate downward with a yielding pressure, but forms a resisting device against which the plate may be forced upward.

When the plunger 76 has been moved downward to force the article resting beneath it upon the supporting device 77 downward through the opening 101, the severed portion of wrapping material will have its sides forced upward against the sides of the article, the article being forced downward to a position wherein its upper face is about in line with the under faces of the sliding folding plate 56 and of the presser plate 108. While it is held in this position, the folder plate 56 is moved forward to the position about as shown in Fig. 15. After this has taken place the plate 13 will move forward, the forward end of same engaging the rear side of the article to push the article, with its wrapper, beneath the presser plate 108. This will fold over the second side of the wrapper, as will be readily understood by reference to Fig. 16, the article being fed forward to a point immediately beneath forming levers 113. These forming levers, of which there are two, (see particularly Figs. 1, 2, 5 and 17), are pivotally mounted at 114 to a support 115, dependent from the upper head 103. The said forming levers 113 have inwardly projecting arms 116 carrying gear sectors in mesh with each other, so that the movements of the two said levers will be synchronous. One of the levers 113 is provided with another arm 117, said arm carrying an anti-friction roller 118 arranged to engage a cam surface 119 upon a bar 120. The cam bar 120 is carried by the support 115, but is arranged to have a relative vertical movement with respect thereto, said cam bar having a lateral projection 121 arranged to engage stationary abutments 122 upon the pedestal or standard 21. A spring 123 tends to draw the levers together and to hold the cam follower roller 118 up against the face of the cam 119.

When the upper head 103 is moved downward, the lever 113, being carried thereby, will be moved downward therewith, and the lower ends of said levers, being opposite the ends of the article to be wrapped and the overhanging portions of the wrapper, as will be seen more clearly by reference to Fig. 5 in which an article is shown in position beneath the forming levers and with a wrapper partially folded around same, will engage the wrapper ends to form a preliminary fold

thereof, as will be seen by reference to Fig. 17, the spring 123 tending to draw the levers together so as to press the ends thereof against the ends of the article to press the fold of the wrapper tightly against same. 70 Near the end of the downward movement of the levers the lateral projection 121 of the cam bar 120 will come into engagement with the lowermost abutment 122, whereby the same will be held stationary during continued downward movement of the levers, so as to rock the levers outward against the resistance of the spring 123. During the upward movement, therefore, of these parts, the levers will be held outward and clear of 80 the ends of the article, and clear also of certain rotating folding members which will now be operated, and will not be free to move inward until they arrive near the completion of the upward movement thereof, 85 when the projection 121 of the cam bar 120 will strike the upper abutment 122 to bring the lower portion of the cam face 119 opposite the roller 118, and then the levers will again be free to move inward as before. 90

After the ends of the wrapper have been operated upon by the forming levers 113 so as to form the first operation of the end folds, and the forming levers have been moved outward in the manner above set forth, rotary 95 folding members 124, 124, will be rotated against the ends to turn over the rearward projecting flaps thereof. This operation is shown in Fig. 18 the said folding members appearing clearly also in Figs. 3 and 5. 100 These folding members 124 are mounted, respectively, on shafts 125, 125, suitably journaled in the frame of the machine, said shafts provided at their outer ends, respectively, with gear-wheels 126, 126. The said gear-wheels 126 are in mesh, respectively, with gear-wheels 127, 127 upon an operating shaft 128, said operating shaft also journaled in bearings in the main frame. At its rear end, the shaft 128 is provided with a mutilated 110 driving pinion 129 (see particularly Figs. 3, 4, 5 and 6), said mutilated driving pinion arranged to be engaged by a mutilated driving gear 130 upon the main shaft 2 of the machine. 115

The operating parts of the machine are so timed, that while this last operation was being performed, the reciprocating plate 13, and parts carried thereby, will have moved rearwardly, and the cam 51 will, through its connections, have acted upon the movable bar 35, so as to move it relatively rearward with respect to the stationary bar 32, to open the gripper member 36. At the rear of the gripper member, the bar 35 carries a dog 131, the said dog being pivoted to the bar in the same manner as the gripper member 36 is pivoted thereto, and provided with a downwardly extending finger engaging the bar 32, also in a similar manner thereto. When the bar 35 is 125 130

moved to open the gripper jaws, as aforesaid, the dog 131 will also be rocked upon its support, so that the end face thereof will rise above the top surface of the bar 35, and with 5 the parts in this position, will so rise at the rear of the partially wrapped article beneath the forming levers 113. The dog is shown in such position in Fig. 19 of the drawings, while in Fig. 2 the dog is shown in its other 10 position, at rest in an opening in the said bar 35, with its forward end below the upper surface of the said bar. The next forward movement of the plate 13, and hence of the bars 32 and 35 and their co-related parts, will 15 cause the dog 131 to engage the partially wrapped article beneath the forming levers 113, to push the same further forward beneath the presser-plate 108. In being thus pushed forward, the article is pushed between end presser plates 135 (see particularly Figs. 1, 2 and 3), these plates being 20 pressed toward each other by springs 136, backed by abutments 137. The rear shoulders of these end plates will act as cams or 25 abutments to turn over the forward projecting flaps of the end portions of the wrapper as the article is advanced, and the pressure of the plates will cause the folded end portions to press tightly against the article. So far 30 the partially wrapped article is resting upon a support 132, secured to the main frame of the machine, the downwardly projecting end portions lying in convergent ways located between tongues 133 and cam surfaces 134. 35 The action of the cam surfaces 134 upon the advancing article will be to tuck the extremities of the folded wrapper under the article, so that the article so far wrapped will appear about as is shown in Fig. 24 of the 40 drawings. The forward movement of the plate 13 is sufficient to feed the article thus wrapped, to a point immediately above the open end of a delivery chute 138, and immediately beneath a plunger 139. At this point 45 the article will be solely supported by the said presser plates, having been moved completely beyond the end of any bottom support. The article is now completely wrapped, so far as the first wrapping is concerned, and 50 is in a position and condition ready to receive the label.

The labels are arranged in a pile in a suitable magazine 140, the same being removably supported by means of the bracket 141 to the 55 main frame of the machine. The labels in the magazine rest upon a follower 142, said follower provided with a portion 143 constituting a feed nut, the same engaging with a vertical feed screw 144, journaled in bearings 60 stationary with the magazine. The feed nut is provided with a ratchet wheel 145, with which a feed pawl 146 is arranged to engage. The pawl 146 is adjustably pivoted to an arm 147, secured to a rock shaft 148, upon 65 which is also secured a lever 149 carrying a

cam follower 150. The cam follower 150 rests against the face of the cam 151 upon the main shaft 2 of the machine, and the said cam, in its revolution, will rock the shaft 148 to operate the feed pawl, and thus to give a 70 step by step movement of rotation to the feed screw 144. This will slowly raise the follower 142 to lift the pile of labels, for the purpose of compensating for the labels as 75 they are removed, in the operation of the machine, and the adjustment between the pawl 146 and the arm 147 is intended for the purpose of compensating for varying thicknesses of the said labels. A spring 152 operates to rock the shaft 148 against the action 80 of the cam, and to hold the cam up against the cam face.

Suspended above the label magazine is a gum or paste tube 153, said gum or paste tube being suitably supported by means of a 85 bracket 154 upon the upper head 103. A thumb screw 155 is preferably provided for the purpose of securing the tube 153 in place, so that it may be readily removed when desired. 90

At its foot, the tube 143 has secured to it a foot piece 156, said foot piece carrying a valve 157, having a dependent stem 158 which protrudes through the bottom thereof. It will be understood that, upon the reciprocation of the head 103, as above set forth, the paste tube 153 will also be reciprocated, being moved downward from the position in which it is shown in the drawings toward the labels in the magazine, until, finally, 95 the stem 158 will engage the topmost label and the valve will be brought to rest. A slight continued downward movement of the tube will open the valve and a small quantity of paste or gum will flow through the valve 100 opening from the tube to effect a constant but slight feed of paste or gum to the valve stem and thus to the label when the said stem engages it. The label will thus be caused to stick to the stem 158 of the valve 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780

As before explained, the moment the bars carrying the gripper members get to the foremost position in their reciprocation, the jaws will snap to a closed position by engagement of the cam piece 41 with the abutment 47, 125 and the label will be firmly gripped thereby. Upon the return movement of the bars 32 and 35 with the plate 13, the label thus gripped will be carried rearwardly to the position in which it is shown in Fig. 2, and di- 130

rectly above the open mouth of the delivery chute 138 beneath the wrapped article, held between the end presser plates 135 and in a line with the plunger 139. Upon the next 5 downward movement of the upper head 103 the plunger 139 will be carried down and will engage the top of the article to force same downward upon the label held thus waiting in position, and then still further downward 10 into a receiver 159 arranged at the receiving end of the delivery chute.

Cheek pieces 160 are arranged at the rear and front of the forward path of movement of the article above the receiver 159, so that, 15 in being so forced downward, the label is given an initial fold, as is clearly shown in the diagram Fig. 21. The receiver 159 has a spring pressed front wall 161, so that the articles thus forced therein will be held laterally 20 under yielding pressure. They are, at the same time, of course, supported by other articles which have gone before, after the first few articles have been delivered, and the delivery chute is filled up to this point. In forcing 25 the article with the label thus partially folded around it downward, the upper edge of the article is caused to be brought about in line with the under faces of folding plates 162, 163, the said folding plates being arranged to 30 reciprocate in a path immediately above the said article, and, in their reciprocation, to fold the projecting sides of the label over the upper face of the wrapped article. When the article is pushed downward by the plunger 35 35 as above described, both of the folding plates 162, 163 will be retracted so that the path of movement for the article will be clear, as shown in Fig. 21, but, immediately the article has been so pushed downward and the 40 plunger 139 has been withdrawn by the upward movement of the upper head 103, the forward folding plate 162 will be reciprocated above the article, as shown in Fig. 22, with the result that the front projecting portion 45 of the label will be folded over. This plate 162 is reciprocated by means of a lever 164, which is secured to the rock shaft 148. This lever engages the said plate 162 and causes same to move backward and forward to effect 50 the first fold of the label every time the rock shaft 148 is moved by the above mentioned cam 151. This cam, therefore, is employed for the double purpose of operating the said 55 first folder plate and the perpendicular feed for the label magazine. Directly this first fold has been completed, the second fold may be made by means of the second folding plate 163, which is engaged for this purpose by a lever 165, provided with a cam follower 166 60 in engagement with a cam 167 upon the main shaft of the machine. The cam 167 is timed to move the plate 163 forward at the right moment to complete the last fold of the label as the plate 162 recedes, and the end of the 65 label thus folded over having been provided

with a modicum of gum or paste, the last fold will be pasted down so as to securely fasten the label in position.

The article is now completely wrapped and the label fastened on and is in the receiving 70 end of the delivery chute. Successive deliveries of successive articles will force the said articles down the delivery chute one on top of the other, from whence they may be removed as is desired. I have, however, provided 75 means for removing the article from the said chute in batches of a predetermined number as follows: At the side of the chute, near the forward end thereof, is arranged a pusher 168, arranged to have a lateral move- 80 ment across the chute to eject articles therefrom. The width of the pusher face is of a dimension sufficient to include the predetermined number of articles desired to be ejected. The pusher as a whole includes a 85 slide 169 mounted in guideways 170, and the said pusher is normally held in a rest position in the said guideways, but may be given a lateral path of movement across the delivery chute when desired. The slide portion 90 95 169 is provided with an upwardly projecting lug or abutment 171, with which the moving portion of an operating member is adapted to engage.

The operating member comprises a reciprocating bar 172, said bar being given a constant movement of reciprocation for each revolution of the machine. The bar 172 is pivotally secured at its rear end to an arm 173, arranged upon a rock shaft 174, said 100 rock shaft mounted in bearings 175, and provided with another arm 176 carrying a cam roller 177, which engages with the face of a crown cam 178. The crown cam 178 is mounted upon the main shaft 2 of the 105 machine. At its forward end the reciprocating bar 172 rests upon an anti-friction roller 179, arranged at the end of an arm 180, secured upon a short shaft 181. Secured to the same shaft, and at about right angles thereto, 110 is another arm 182, the end of which is arranged in the path of movement of the articles in the delivery chute. A spring 183 normally presses the arm 182 forward to lift the arm 180, and thus supports the end of 115 the bar 172 at a predetermined height. The bar 172 is provided with a lateral projection 184, which, when the bar is so supported, will travel over the top of the abutment 171 in the reciprocation of the said bar. If the 120 arm 180 be depressed by the forcing forward of the arm 182, by the forward movement of the articles in the chute, as the foremost article engages the said lever, the front end of the operating bar 172 will be allowed to drop 125 to an extent sufficient to cause the lateral projection 184 to engage the abutment 171 in its reciprocation, and at such time, therefore, to move the pusher forward. Thus, when the delivery chute has been completely 130

filled, the engagement of the foremost article will operate to cause the rejection of a number of articles equal to the breadth of the pusher head. In the present drawings, in order to save space, I have shown the delivery chute as quite short, and the width of the pusher head as sufficient only to take in two or three of the articles, but it will be understood that in practice, this may be varied, and the ejecting device may conveniently eject twenty-five, fifty, or more articles at a time. The slide 169 is provided with a second abutment 185, arranged at the rear of the abutment 171, and so located that after the pusher has been moved forward, it will always be moved back again by engagement of the lateral projection 184. The abutment 185 is of such a height that the lateral projection 184 will always engage it, so that, even though the bar has been lifted, when the articles have been ejected from the chute, the rearward movement of the bar 172 will still effect the rearward movement of the pusher.

It is thought that the entire operation of the machine will be quite clear, from the foregoing, but for the sake of additional clearness, attention is called to the following timing of the various parts: A complete reciprocation of the plate 13 with all parts carried thereby, is made during one half of a revolution of the main shaft, and the said parts are held at rest during the other half of the movement of the main shaft. In this movement, the lowermost article from the magazine 75 is pushed to a position beneath the plunger 76, while another article is pushed from a point in line with the said plunger to a position beneath the forming levers 113, and still another article is pushed from a point beneath the forming levers 113 to a position beneath the plunger 139. The first said article is acted upon by the pusher plate 29, the second by the forward end of the plate 13, and the third by the dog 131, carried by the bar 35. During nearly all the time the plate 13 and correlated parts are operating, the overhead mechanism was held stationary, but the said overhead mechanism is given a complete reciprocation, after the various articles have been deposited beneath the plungers 76 and 139 and the forming levers 113, such reciprocation occupying a period of one-half of the revolution of the main shaft 2. By this means, three articles are operated upon simultaneously at each revolution of the machine. It will also be noticed that the feeding periods and the operating periods slightly overlap each other; that though each occupies a period of one-half a revolution of the machine, these two periods do not make up an entire revolution, but, in overlapping each other, as above stated, include a short period, during which all the parts stated are at rest. This rest period is utilized for the purpose of carrying out other operations, so

that at each revolution of the machine, a complete article is delivered, such article, during its passage through the machine, having received quite a large number of treatments. By the foregoing, much time is saved, and the machine will have a capacity of a large number of completely wrapped articles per minute.

The machine is quite simple, considering the amount of work done, being, so far as I am aware, considerably simpler than any other machine designed for the same purpose, now on the market. Further, it will be noted that all the parts are very accessible, so that they may be readily cleaned, renewed or repaired. The overhead parts are all mounted upon a single head 103, and may be removed bodily, if desired, without the necessity of dismantling the other portions of the machine. Similarly, the label magazine and its equivalent may be readily removed, and the remainder of the machine may be almost as readily dismantled by the removal of but a few screws. In order that the overhead parts may be moved out of the way, if desired, without being actually removed, I have constructed the portion which I have described heretofore as the upper head 103 in two parts, one including a bracket 186, provided with a vertical hub, 95 which is directly mounted upon the plunger rod 20, and with a horizontal hub 187, and the other including a horizontal spindle 188, mounted in the said hub 187. The plunger 76, forming levers 113, plunger 139, and paste tube 153, are all suspended from the spindle 188, so that by turning the said spindle in the hub 187, all these parts may be swung clear, so as to permit entirely free access to be had to the remaining portion of the machine. A set screw 189 is provided for locking the parts in their operative position, the said set screw preferably arranged to engage a depression in the spindle 188, to prevent accidental displacement.

What I claim is:

1. In a wrapping machine, the combination with means for simultaneously imparting a step by step movement to a plurality of articles in successive stages during one portion of a cycle of operation of the machine and for feeding and severing wrapping material therefor, of reciprocating means for performing folding operations, operating simultaneously upon the several articles transversely of the direction of the step by step movement thereof during another portion of the cycle of operation of the machine, and folding devices operating intermediate the operation of the said step by step means and the transverse reciprocating means.

2. In a wrapping machine, the combination with a drive shaft, means driven thereby during a portion only of the revolution of the same for simultaneously imparting a step by

step movement to a plurality of articles in successive stages, and means for feeding wrapping material therefor, of reciprocating means for performing folding operations, 5 driven by the main shaft during a portion only of a revolution of the drive shaft for operating simultaneously upon the several articles transversely of the direction of the step by step movement, and folding devices operating by the main shaft during an interval between the operation of the said step by step means and the transverse reciprocating means.

3. In a wrapping machine, the combination with a yielding supporting device arranged to receive an article to be wrapped, and a plunger for engaging the article to be wrapped, when supported upon said device, of means for reciprocating the plunger to 10 force the article down against the resistance of the supporting device, means independent of the plunger for depressing the supporting device upon reciprocation of the plunger when no article is present upon the supporting device, and means for feeding an article forward after it has been forced downward by the plunger.

4. In a wrapping machine, the combination with a yielding supporting device comprising a vertically movable member 30 spring-held in its uppermost position, and means for feeding articles to be wrapped upon said supporting member, of a reciprocating plunger 76 arranged in its reciprocation to engage an article supported upon the member 76 and to depress the said member, and cam operating means to depress the reciprocating device independently of the plunger when no article is supported thereby.

40 5. In a wrapping machine, the combination with a magazine for articles to be wrapped and a plate having an opening at a point in advance of said magazine, a reciprocating feed plate having an abutment for engaging and feeding articles from said magazine to the said opening, and having another abutment secured to move with the first said abutment, for feeding forward articles after they have moved through the said opening, 45 of a yielding support for said articles opposite said opening, and means for forcing articles through the said opening against the resistance of said yielding support.

6. In a wrapping machine, the combination with a reciprocating member having a portion constituting a carrying member, and a finger engaging same and longitudinally movable therewith, of means for supplying wrapping material to said carrying member 55 and for supplying articles to be wrapped to a point above said carrying member, a pusher secured to said carrying member arranged to overhang the wrapping material supported upon said carrying member, and to engage 60 the side of an article to be wrapped to feed

same forward with the wrapper and carrying member, means for reciprocating the carrying member, and means for lifting the clamping finger during the rearward portion of the reciprocating movement of the carrying member. 70

7. In a wrapping machine, the combination with a stationary top plate having a longitudinal groove therein, of a reciprocating feed plate having a portion fitted to said longitudinal groove, a clamping finger longitudinally movable with said reciprocating plate, but arranged to have a movement transversely into and out of engagement with the portion of said reciprocating plate in the 75 groove of said stationary plate, a magazine for articles to be wrapped arranged above the groove in said top plate, and a pusher, reciprocating with said reciprocating plate, arranged to overhang said top plate and the 80 longitudinal groove therein.

8. In a wrapping machine, the combination with a reciprocating carrying member having a plane face arranged to support a ribbon of wrapping material, and a clamping finger yieldingly forced against the surface of said carrying member to grip the wrapping material between itself and the said carrying member, of a magazine for articles to be wrapped arranged above the carrying member 90 and at the rear of the path of movement of the clamping finger, feeding means for the said articles comprising a plate which overhangs the said carrying member, and between which and the said carrying member 95 the wrapping material has its path of movement, means for reciprocating the said carrying member the feed plate and the clamping finger, and means for lifting the said clamping finger during the rearward portion of the 100 reciprocation of the carrying member.

9. In a wrapping machine, the combination with a reciprocating bar 27 constituting a carrying member for carrying wrapping material and also an article to be wrapped, a 110 magazine for articles to be wrapped arranged above the carrying member, feeding means for the said articles, and a clamping finger 59 provided with a spring 63 for pressing it toward the said carrying member, of a rocking bar 61 supporting the said clamping finger, means reciprocating with the said bar 27 for engagement with the clamping finger to reciprocate same therewith, and means for lifting the said clamping finger during the 115 return portion of its reciprocating movement.

10. In a wrapping machine, the combination with a reciprocating bar 27 constituting a carrying member for carrying wrapping material and also an article to be wrapped, 120 a magazine for articles to be wrapped arranged above the carrying member, feeding means for the said articles, and a clamping finger 59 provided with a spring 63 for pressing it toward the said carrying member, of 125 130

a rocking bar 61 supporting the said clamping finger, means reciprocating with the said bar 27 for engagement with the clamping finger to reciprocate same therewith, such movement being a sliding movement with respect to the rocking bar supporting same, a gear segment 65 secured to said rocking bar 61, a gear sector 66 engaging said gear segment, and a cam 69 for rocking said gear sector to lift the clamping finger during its return movement.

11. In a wrapping machine, the combination with a reciprocating carrying member having a plane face arranged to support a ribbon of wrapping material, and a clamping finger yieldingly forced toward the plane surface of said carrying member to grip the wrapping material between itself and the said carrying member, of a magazine for articles to be wrapped arranged above the carrying member, and at the rear of the path of movement of the clamping finger, feeding means for the said articles means for reciprocating the said carrying member the feeding means and the clamping finger, means for severing the wrapping material at a point between the clamping finger and the magazine after the carrying member and clamping finger have been moved forward, and means for lifting the clamping finger during its return movement.

12. In a wrapping machine, the combination with a plate having an opening therein, and means for feeding a ribbon of wrapping material over said opening, of a severing device for severing a section of the said wrapping material, steadyng means engaging the severed portion of the wrapping material contiguous to the said opening, and means for lifting the said steadyng means prior to a feeding movement of the wrapping material.

13. In a wrapping machine, the combination with a plate having an opening therein, means for feeding a ribbon of wrapping material over said opening, and means for feeding articles upon said wrapper to a point over said opening, of a severing device for severing a section of the said wrapping material, steadyng means engaging the severed portion of the wrapping material contiguous to the said opening, means for lifting the said steadyng means after the section of wrapping material has been so severed, and means for forcing the article with the portion of the wrapper upon which it rests, through the said opening.

14. In a wrapping machine, the combination with a plate having an opening therein, means for feeding a ribbon of wrapping material over said opening, means for feeding articles upon said wrapper to a point over said opening, and a yielding supporting device in line with said opening arranged to receive and support a portion of the wrapping material and an article to be wrapped therein,

of a severing device for severing a section of the said wrapping material, steadyng means engaging the severed portion of the wrapping material contiguous to the said opening, and means for forcing the article with the portion of the wrapper upon which it rests through the said opening against the resistance of the supporting device.

15. In a wrapping machine, the combination with a top plate 25, and a plate 108 having arms 109 pivoted to the said plate 25, said top plate, pivoted plate and arms thereof inclosing a space 101 through which an article is adapted to be forced, of means for forcing an article through said opening and for advancing same beneath said pivoted plate 108, a plunger 110 pivoted to said plate 108, a housing 111 therefor and a spring 112 within said housing bearing against said plunger, substantially as specified.

16. In a wrapping machine, the combination with folding devices, of a reciprocating feed plate having a relatively stationary shoulder or abutment for engaging and feeding an article during one step of its wrapping operation, and having a relatively movable dog for engaging an article during another step of the wrapping operation, and means comprising a pivoted cam carried by the feed plate, and operated at predetermined points in a cycle of movements of the machine, for moving the dog out of operative position during the return portion of the reciprocating movement of the feed plate.

17. In a wrapping machine, the combination with folding devices, of a reciprocating feed plate having two relatively stationary abutments in different planes for feeding forward two articles in different steps of the wrapping operation, and having a relatively movable dog for engaging an article during another step of the wrapping operation, and means for moving the dog out of operative position during the return portion of the reciprocating movement of the feed plate.

18. In a wrapping machine, the combination with folding devices, of a reciprocating feed plate 13 provided with an overhanging pusher plate 29, and having a shoulder or abutment which has a path of movement lower than the path of movement of the pusher plate, a movable abutment 131 arranged to be moved into line with the path of movement of the shoulder or abutment, and means for moving the same out of such line of movement.

19. In a wrapping machine, the combination with folding devices, and a reciprocating feed plate, of a relatively stationary bar secured to said feed plate, a relatively movable bar carried by said feed plate, a feed dog pivoted to one of said bars and engaging the other, and means for shifting the position of said movable bar with relation to the stationary bar.

20. In a wrapping machine, the combination with a reciprocating feed plate, of a relatively movable bar carried thereby, a feed dog pivoted to said bar and engaging a portion stationary with said feed plate, means for reciprocating said feed plate, means for engaging the said bar to shift its position with relation to the feed plate at about the end of the forward movement of the said feed plate, including a device for locking the said feed plate and bar together in their adjusted positions during the major portion of the movement thereof in either direction.
21. In a wrapping machine, the combination with a reciprocating feed plate, of a relatively movable bar carried thereby, a feed dog pivoted to said bar and engaging a portion stationary with said feed plate, means for reciprocating said feed plate, a stationary abutment engaging said bar near the end of the forward movement of the feed plate to shift the relative position thereof, and cam operated means operating independently of the movement of the feed plate, for reversing the relative position of said movable bar with respect to said feed plate during another portion of the movement of said feed plate.
22. In a wrapping machine, the combination with a reciprocating feed plate, of a relatively movable bar carried thereby, a feed dog pivoted to said bar and engaging a portion stationary with said feed plate, means for reciprocating said feed plate, a stationary abutment engaging said bar near the end of the forward movement of the feed plate to shift the relative position thereof, a cam, and means operated thereby for reversing the relative position of said movable bar with respect to said feed plate during another portion of the movement of said feed plate.
23. In a wrapping machine, the combination with a reciprocating feed plate, of a relatively movable bar carried thereby, a feed dog pivoted to said bar and engaging a portion stationary with said feed plate, a cam piece carried by said feed plate and engaging a part carried by said bar, and means for shifting the position of said cam piece at different points in the reciprocation of said feed plate.
24. In a wrapping machine, the combination with a reciprocating feed plate, of a relatively movable bar carried thereby, a feed dog pivoted to said bar and engaging a portion stationary with said feed plate, a cam piece carried by said feed plate and engaging a part carried by said bar, a stationary abutment for engaging said cam piece to operate same during one portion of the reciprocation of the feed plate, and mechanically operated means for shifting the cam piece during another portion of the movement of the feed plate.
25. In a wrapping machine, the combination with a reciprocating feed plate, of a relatively movable bar carried thereby, a feed dog pivoted to said bar and engaging a portion stationary with said feed plate, a cam piece carried by said feed plate and engaging a part carried by said bar, a stationary abutment for engaging said cam piece to operate same during one portion of the reciprocation of the feed plate, a rotary cam, and means operated thereby for shifting the position of the cam piece during another portion of the reciprocation of the feed plate.
26. In a wrapping machine, the combination with a reciprocating feed plate 13, a movable bar 35 carried thereby, a pivoted dog 131 pivoted to said bar and engaging a portion stationary with said plate 13, a cam roller 43 secured to said bar 35, a cam piece 41 pivoted to a portion stationary with said plate 13, said cam piece having notches 44, 45 at different distances from the pivotal center of said cam piece, and means for operating said pivoted cam piece.
27. In a wrapping machine, the combination with means for folding the sides of a wrapper around an article and for feeding the article, with its wrapper so partially folded, beneath forming levers, of pivoted forming levers, means for reciprocating the forming levers across the ends of the article to fold down the projecting ends of the wrapper, and means for forcing the levers apart during the return portion of the reciprocating movement so that they will clear the ends of the article.
28. In a wrapping machine, the combination with means for folding the sides of a wrapper around an article and for feeding the article, with its wrapper so partially folded, beneath forming levers, and pivoted forming levers spring pressed toward each other, means for reciprocating the forming levers across the ends of the article to fold down the projecting ends of the wrapper, and means for forcing the levers apart against their spring tension during the return portion of the reciprocating movement, so that they will clear the ends of the article.
29. In a wrapping machine, the combination with means for folding the sides of a wrapper around an article and for feeding the article, with its wrapper so partially folded, beneath forming levers, of pivoted forming levers having intermeshing gear sector portions, means for reciprocating the forming levers across the ends of the article to fold down the projecting ends of the wrapper, and means for forcing the levers apart during the return portion of their reciprocating movement to cause them to clear the ends of the article at such time.
30. In a wrapping machine, the combination with means for folding the sides of a wrapper around an article and for feeding the

article, with its wrapper so partially folded, beneath forming levers, of pivoted forming levers having intermeshing gear sector portions, spring means for forcing the said levers together, means for reciprocating the forming levers across the ends of the article to fold down the projecting ends of the wrapper, and means acting upon one of the arms to separate the said arms against spring tension during the return portion of the movement thereof.

31. In a wrapping machine, the combination with means for folding the sides of a wrapper around an article and for feeding the article, with its wrapper so partially folded, beneath forming levers, of pivoted forming levers, means for reciprocating the forming levers across the ends of the article to fold down the projecting ends of the wrapper, and a cam piece for separating the levers upon the return portion of their reciprocating movement.

32. In a wrapping machine, the combination with means for folding the sides of a wrapper around an article and for feeding the article, with its wrapper so partially folded, beneath forming levers, of pivoted forming levers, a carrier therefor, a cam piece carried by the said carrier, the said cam piece in its movement arranged to force the forming levers apart, means for reciprocating the carrier and forming levers carried thereby, and stationary abutments engaging the said cam piece, substantially as set forth.

33. In a wrapping machine, the combination with means for folding the sides of a wrapper around an article and for feeding the article, with its wrapper so partially folded, beneath forming levers, of pivoted forming levers 113 having intermeshing gear sectors 116, a spring for forcing the two levers together, a cam follower carried by one said forming lever, a carrier 115 carrying the said forming levers, a cam piece 120 upon said carrier arranged to engage said cam follower, means for reciprocating the carrier and forming levers, and stationary abutments 122 for engaging the said cam piece.

34. In a wrapping machine, the combination with means for folding the sides of a wrapper around an article and for feeding the article, with its wrapper so partially folded, beneath forming levers, of forming levers, means for moving the forming levers in one direction across the ends of the article to fold down the projecting ends of the wrapper and for returning the same to an initial position, means for moving the levers away from contact with the ends of the article during the return movement, rotary forming members for performing a folding operation upon the wrapper ends, and means for rotating the said members during the return movement of the forming levers.

35. In a wrapping machine, the combina-

tion with means for folding a wrapper in one direction around an article, and forming mechanism for folding down the projecting ends of the said partially folded wrapper, of folding means for folding over the rearward projecting end flaps, end plates having shoulders or abutments, cam members arranged beneath said plates and immediately in advance of the shoulders or abutments thereof, and means for imparting a single movement in right lines to said article past said shoulders or abutments and said cam members, whereby the former will operate to fold over the forward projecting end portions, and the latter to tuck the projecting extremities beneath the article.

36. In a wrapping machine, the combination with means for folding a wrapper in one direction around an article, and forming mechanism for folding down the projecting ends of the said partially folded wrapper, of a runway for the article having spring-pressed sides arranged immediately in advance of the point at which the said forming mechanism operates, for engaging the forward projecting end portions of the wrapper as the article is fed forward, rotary forming members pivoted about an axis immediately at the rear of said point arranged in their operation to fold over the rearward projecting end flaps, the bottom of the runway cut away at a point in advance of the portion at which the said abutments or shoulders are located, and provided with cam elements which are adapted to engage the downwardly projecting extremities of the wrapper, and feeding means for applying a single impulse to an article to feed it from the said point at which the said forming mechanism operates to a point beyond the said cam members, whereby the forward projecting end flaps will be folded over and the extremities tucked under the article, all in substantially one operation.

37. In a wrapping machine, the combination with a feed plate having an abutment for engaging an article, and means for reciprocating the feed plate, of a gripper jaw carried stationary with the feed plate, a relatively movable bar carried by said feed plate, a gripper jaw pivoted to said relatively movable bar and engaging a part stationary with the feed plate, a label magazine, and means for lifting labels one at a time from the magazine and presenting them to the gripper jaws.

38. In a wrapping machine, the combination with a feed plate having an abutment for engaging an article, and means for reciprocating the feed plate, of a gripper jaw carried stationary with the feed plate, a relatively movable bar carried by said feed plate, a gripper jaw pivoted to said relatively movable bar and engaging a part stationary with the feed plate, means for shifting the position of the relatively movable bar with respect to

the feed plate and for retaining it in its adjusted position, a label magazine, and means for lifting labels one at a time from the magazine and presenting them to the gripper jaws.

5 39. In a wrapping machine, the combination with a feed plate having an abutment for engaging an article, and means for reciprocating the feed plate, of a gripper jaw carried stationary with the feed plate, a relatively movable bar carried by said feed plate, a gripper jaw pivoted to said relatively movable bar and engaging a part stationary with the feed plate, a cam piece carried by said feed plate and adapted to operate said movable bar, means for operating said cam piece, a label magazine, and means for lifting labels one at a time from the magazine and presenting them to the gripper jaws.

15 40. In a wrapping machine, the combination with a feed plate having an abutment for engaging an article, and means for reciprocating the feed plate, of a gripper jaw carried stationary with the feed plate, a relatively movable bar carried by said feed plate, a gripper jaw pivoted to said relatively movable bar and engaging a part stationary with the feed plate, a cam piece carried by said feed plate and adapted to operate said movable bar, a stationary abutment for engaging and operating said cam piece at about the limit of the forward movement of the feed plate, a label magazine, and means for lifting labels one at a time from the magazine and presenting them to the gripper jaws.

35 41. In a wrapping machine, the combination with a feed plate having an abutment for engaging an article, and means for reciprocating the feed plate, of a gripper jaw carried stationary with the feed plate, a relatively movable bar carried by said feed plate, a gripper jaw pivoted to said relatively movable bar and engaging a part stationary with the feed plate, a cam piece carried by said feed plate and adapted to operate said movable bar, an operating cam, and intermediate mechanism between said operating cam and said cam piece to shift the position of said cam piece at a predetermined position of the reciprocating feed plate, a label magazine, and means for lifting the labels one at a time from the magazine and presenting them to the gripper jaws.

55 42. In a wrapping machine, the combination with a feed plate having an abutment for engaging an article, and means for reciprocating the feed plate, of a gripper jaw carried stationary with the feed plate, a relatively movable bar carried by said feed plate, a gripper jaw pivoted to said relatively movable bar and engaging a part stationary with the feed plate, a cam piece carried by said feed plate and adapted to operate said movable bar, a stationary abutment for engaging the cam piece to operate same near the limit of the forward movement of the feed plate,

an operating cam, and mechanism between the operating cam and the cam piece to operate the said cam piece when the feed plate is in another position, a label magazine, and means for lifting labels one at a time from the magazine and presenting them to the gripper jaws.

5 43. In a wrapping machine, the combination with a reciprocating feed plate 13 and means for reciprocating same, of a stationary gripper jaw 34 carried thereby, a relatively movable bar 35 carried by said feed plate, another gripper jaw 36 pivoted to said movable bar and engaging a portion stationary with said feed plate, a cam piece 41 pivoted to a portion stationary with said feed plate, said cam piece having two notches 44 and 45 at different distances from the pivotal center of said cam piece, a spring 40 between said feed plate and said movable bar, and means for operating said cam piece.

15 44. In a wrapping machine, the combination with a reciprocating feed plate 13 and means for reciprocating same, of a stationary gripper jaw 34 carried thereby, a relatively movable bar 35 carried by said feed plate, another gripper jaw 36 pivoted to said movable bar and engaging a portion stationary with said feed plate, a cam piece 41 pivoted to a portion stationary with said feed plate, said cam piece having two notches 44 and 45 at different distances from the pivotal center of said cam piece, a spring 40 between said feed plate and said movable bar, a stationary abutment 47 for engaging the cam piece 41 near the end of the forward movement of the reciprocating feed plate, an operating cam, and intermediate mechanism between said operating cam and said cam piece to operate same when the reciprocating feed plate is in another position.

35 45. In a wrapping machine, the combination with wrapping and feeding means, of a label magazine, having a movable follower for supporting a pile of labels, a paste receiver, a member arranged to receive paste from the receiver, means for reciprocating the said member toward and away from a pile of labels in the magazine, to cause said member to engage the topmost label and to lift same by adhesion, a gripper, means for operating and reciprocating same, and automatic feeding means comprising a feed screw for the follower, step by step mechanism for the feed screw, and means for adjusting the throw of the step by step mechanism to vary the extent of movement imparted to the feed screw at each operation.

55 46. In a wrapping machine, the combination with a horizontally reciprocating feed plate having abutments for engaging and feeding articles in different planes, of overhead mechanism, including means for engaging an article and transferring it from one said plane to another, and folding means for

simultaneously engaging another article which has been previously so transferred, and means for vertically reciprocating said overhead mechanism.

47. In a wrapping machine, the combination with a horizontally reciprocating feed plate having three abutments for simultaneously engaging and feeding forward three articles in successive stages in the machine, the first of said abutments arranged upon a different plane to the other two, and the last of said abutments arranged to be lowered out of the feeding plane during the rearward portion of the reciprocating movement of said feed plate, of overhead mechanism comprising plungers adapted to operate upon the articles fed forward by the first and last of said abutments, and forming means adapted to operate upon the article fed forward by the intermediate said abutment; and means for vertically reciprocating said overhead mechanism.

48. In a wrapping machine, the combination with feed mechanism, of a reciprocating

upper head, and operating elements carried by said upper head, adjustable thereon, whereby they may be moved into and out of operative position.

49. In a wrapping machine, the combination with feed mechanism, of an upper head, operating elements pivotally carried by said upper head, and means for bodily reciprocating said upper head and operating elements.

50. In a wrapping machine, the combination with feed mechanism, of an upper head, a plunger and forming members pivotally carried by said upper head, means for securing the same in their adjusted position, and means for bodily reciprocating said upper head and parts carried thereby.

In testimony whereof I have hereunto set my hand in the presence of two witnesses.

JAMES J. SULLIVAN.
